UNITED STATES PATENT OFFICE.

WILLIAM B. McMURTIE AND JOHN W. MOORE, OF SHIDLER, OKLAHOMA.

CASING-RIPPING DEVICE.

Application filed June 24, 1924. Serial No. 722,089.

To all whom it may concern:

Be it known that we, WILLIAM B. McMURTIE and JOHN W. MOORE, citizens of the United States, residing at Shidler, in the 5 county of Osage and State of Oklahoma, have invented certain new and useful Improvements in a Casing-Ripping Device, of which the following is a specification.

This invention relates to new and useful 10 improvements in means for ripping casings in oil wells whereby the same may be salvaged in a more efficient and simple manner.

One of the important objects of the present invention is to provide a casing ripping 15 device of the above mentioned character, which may be readily and easily placed in position for ripping the outer casing of a pair of concentrically arranged pipes or casings, means being provided for moving the 20 ripping knife to an operative position automatically upon the vertical sliding movement of the body member which supports the knife.

A still further object of the invention is 25 to provide a casing ripping device of the above mentioned character, which is simple in construction, inexpensive, strong and durable and furthermore adapted for the purposes for which it is designated.

Other objects and advantages of this 30 invention will become apparent during the course of the following description.

In the accompanying drawings forming a part of this specification and in which like 35 numerals designate like parts throughout the same:

Figure 1 is a sectional view through the device showing the same in position within the outer casing with the ripping knife in an 40 inoperative position;

Fig. 2 is a similar view showing the ripping knife in an operative position;

Fig. 3 is a side elevation of the casing ripping device showing the guide means for the 45 ripping device;

Fig. 4 is a sectional view taken approximately on line 4—4 of Fig. 1;

Fig. 5 is a similar section taken approximately on line 5—5 of Fig. 1; and

Fig. 6 is a vertical sectional view taken approximately on line 6—6 of Fig. 3.

In the drawings wherein for the purpose of illustration is shown the preferred embodiment of our invention the numerals 1 55 and 2 designate inner and outer casings or pipes which are ordinarily embedded in the

ground, the outer casing 1 forming a protector for the inner casing 2 through which extends the usual mechanism provided for producing oil and gas in the manner well known in the art. The purpose of the present invention resides in the provision of a means whereby the outer casing 1 may be salvaged and to this end we provide a ripping device designated generally by the 60 numeral 3 in the drawing with reference more particularly to Figure 3.

The ripping device comprises a cylindrical body portion 4 which is provided with an eccentric bore 5, the purpose of which is to 65 provide a means whereby the cylindrical body may extend into the outer casing 1 and around the inner casing 2 in the manner clearly illustrated in Figures 1 and 2 of the drawings. The upper end of the cylindrical body portion 4 is provided with a reduced 70 extension 6 which terminates in the threaded tapered end 7 for receiving an operating tool of any well known construction for 75 facilitating in the operation of the casing 80 ripping device.

The lower portion of the cylindrical body 85 4 is provided with a vertically extending groove or channel 8 and the same communicates with a suitable opening 9 provided in the bottom of the cylindrical body portion 4, the purpose of which will hereinafter be 90 more fully described. The portion of the cylindrical body 4 adjacent the vertical channel or groove 8 are cut away as illustrated at 10 on each side of the channel whereby a pair of parallel spaced arms 11 and 12 respectively are provided, the same being further provided with longitudinally 95 extending guide slots 13. The guide slots 14 are inclined downwardly to cooperate with the cut away portions 10 and whereby the back portion of the vertical channel 8 forms a wedge in the manner as illustrated at 15 in the drawings.

Adapted for vertical sliding movement in the channel 8 is the ripper knife 15 and the same is provided with the lateral projection 16 which cooperates with the downwardly inclined guide slot 13 for supporting the 105 ripper knife in proper position.

Associated with the cylindrical body 4 is the frictional member designated generally by the numeral 17 and the same comprises a substantially rectangular shaped frame 110 which is arcuate in cross section in the manner clearly illustrated in Figure 4 of the

drawings. Extending through the frame are the flat springs 18 and 19 respectively, the lower ends of which are secured to the lower portion 20 of the frame by means of fastening bolts 21. The upper ends of the spring elements 18 and 19 are adjustably secured together by means of the bolt 22 and the nuts 23 associated therewith, the same extending through the upper cross piece 24 of the frame. There are a pair of each of these spring elements supported in the frame 17 on each side of the central partition 25 in the manner clearly illustrated in Figure 3 of the drawings.

15 The purpose of the spring elements is to provide a means for engagement with the inner and outer casing for frictionally supporting the member 17 in position between the casings and the purpose thereof will also 20 hereinafter be more fully described. The upper and lower cross bars of the frictional member 17 are provided with centrally arranged registering openings which openings are further adapted to register with the 25 opening 9 provided in the bottom of the cylindrical member 4. It is of course to be understood that the frictional member 17 is disposed below the cylindrical member in the manner more clearly illustrated in Figures 1, 2 and 3 of the drawings. Extending longitudinally through the frictional member 17 through the opening provided therein and also through the opening 9 in the lower portion of the cylindrical member 4 is the 30 stem 26.

35 The stem is of a suitable length and has supported on the lower end thereof the nut 27 which is adapted for engagement with the lower cross bar 20 of the frame 17 while the 40 upper end of the stem has secured thereto the ripper knife engaging head 28. The intermediate portion of the stem 26 has a recess 29 provided in the outer side thereof and pivotally supported therein at 30 at its 45 upper end is the trip 31. A coil spring 32 is associated with the trip 31 and the rear wall of the recess for normally holding the trip lever in an operative position in the manner more clearly illustrated in Figure 2 50 of the drawing.

55 The operation of our improved casing device may be briefly stated as follows—The cylindrical member 4 and the frictional member 17 are inserted into the casing 1 so that the inner casing 2 will be received in the eccentric bore 5. The parts are placed in the casing 1 in such a manner as to be disposed in a position as shown in Figure 1 of the drawings. With the parts arranged 60 as shown in Figure 1, the springs 18 and 19 will hold the frictional member in engagement with the outer and inner casing respectively and will be prevented from moving with the cylindrical body portion 4. The ripper knife 15 will be disposed in its lower-

most position and out of engagement with the casing 1 as also clearly illustrated in Figure 1.

Upon the upward movement of the cylindrical body, the friction member 17 is left 70 behind, until it has reached the terminal 27 of the shaft 26, upon which the trip 31 will have cleared the partition 25, thereby locking the member 17 from any substantial longitudinal movement on the stem 26. 75 Then, in order to bring the ripper 15 into engagement, it is necessary to give the entire tool a downward motion, whereupon the friction means 17 will force the ripper 15 upwardly and relative to the cylindrical body, and along the slot 13 and wedge portion 14, whereby it is forced into cutting position.

By ripping the outer casing 1, the same 85 may be salvaged more easily and efficiently and will also save considerable time in extracting the section of the outer casing. The simplicity of our device enables the same to be readily and easily placed in an operative position and will furthermore be positive in 90 its operation. Furthermore, a casing ripping device of the above mentioned character, may be manufactured at a very low cost and will be strong and durable.

95 While we have shown the preferred embodiment of our invention, it is to be understood that various changes in the size, shape and arrangement of parts may be resorted to without departing from the spirit of the invention and the scope of the appended 100 claims.

Having thus described described the invention, what we claim is:

1. In a casing ripping device, a cylindrical body provided with an eccentrically disposed bore extending longitudinally thereof, thereby providing a comparatively thick side and a comparatively thin side, a stem extending from the end of the comparatively thick side, said thick side of the cylinder body being provided with an exterior vertically inclined opening, a knife having a projection slidably located in the opening, and means for moving the knife with relation to the body.

105 2. In a ripping device, a cylindrical body having a longitudinally extending eccentrically disposed bore so as to provide a comparatively thick side and a comparatively thin side, a stem extending from the end of the comparatively thick side of the body, said comparatively thick side of the body provided with an exteriorly disposed longitudinally extending recess having its inner 110 wall inclined so that the depth of said recess is less at its top than at its bottom, the side walls of said recess being provided with slots extending parallel with each other and with the inclined inner wall, a knife slidable along the inclined inner wall of the recess 115 and provided with projections slidable in the 120

125 130

slots, and means for moving the knife with relation to the body, said means including a trip carried by the body and connected with the knife.

5. 3. In a ripping device, a cylindrical body having a longitudinally extending eccentrically disposed bore so as to provide a comparatively thick side and a comparatively thin side, a stem extending from the end of 10 the comparatively thick side of the body, said comparatively thick side of the body provided with an exteriorly disposed longitudinally extending recess having its inner wall inclined so that the depth of said recess is 15 less at its top than at its bottom, the side walls of said recess being provided with slots extending parallel with each other and with the inclined inner wall, a knife slideable along

the inclined inner wall of the recess and provided with projections slideable in the 20 slots, means for moving the knife with relation to the body, said means including a stem connected with the knife and extending along the body beyond the bottom end thereof, a friction member slideable on the stem, 25 a trip pivoted to an intermediate portion of the stem, and a spring associated with the trip to hold it extended outwardly from the stem, said trip adapted to engage the upper end of the friction member when disposed 30 at the bottom of the stem.

In testimony whereof we affix our signatures.

WILLIAM B. McMURTIE.
J. W. MOORE.
